(57) **CLAIM**

The ornamental design for a box, as shown and described.

DESCRIPTION

The file of this patent contains at least one drawing executed in color. Copies of this patent with color drawings will be provided by the Office upon request and payment of the necessary fee.

FIG. 1 is a front, top, left perspective view of a first embodiment of a box;

FIG. 2 is a rear, top, right perspective view thereof;

FIG. 3 is a front view thereof;

FIG. 4 is a rear view thereof;

FIG. 5 is a right side view thereof;

FIG. 6 is left side view thereof;

FIG. 7 is a top plan view thereof;

FIG. 8 is a bottom plan view thereof;

FIG. 9 is a front, top, left perspective view of a second embodiment of a box;

FIG. 10 is a rear, top, right perspective view thereof;

FIG. 11 is a front view thereof;

FIG. 12 is a rear view thereof;

FIG. 13 is a right side view thereof;

FIG. 14 is left side view thereof;

FIG. 15 is a top plan view thereof;

(Continued)

FIG. 16 is a bottom plan view thereof;
FIG. 17 is a front, top, left perspective view of a third embodiment of a box;
FIG. 18 is a rear, top, right perspective view thereof;
FIG. 19 is a front view thereof;
FIG. 20 is a rear view thereof;
FIG. 21 is a right side view thereof;
FIG. 22 is left side view thereof;
FIG. 23 is a top plan view thereof;
FIG. 24 is a bottom plan view thereof;
FIG. 25 is a front, top, left perspective view of a fourth embodiment of a box;
FIG. 26 is a rear, top, right perspective view thereof;
FIG. 27 is a front view thereof;
FIG. 28 is a rear view thereof;
FIG. 29 is a right side view thereof;
FIG. 30 is left side view thereof;
FIG. 31 is a top plan view thereof;
FIG. 32 is a bottom plan view thereof;
FIG. 33 is a front, top, left perspective view of a fifth embodiment of a box;
FIG. 34 is a rear, top, right perspective view thereof;
FIG. 35 is a front view thereof;
FIG. 36 is a rear view thereof;
FIG. 37 is a right side view thereof;
FIG. 38 is left side view thereof;
FIG. 39 is a top plan view thereof;
FIG. 40 is a bottom plan view thereof;
FIG. 41 is a front, top, left perspective view of a sixth embodiment of a box;
FIG. 42 is a rear, top, right perspective view thereof;
FIG. 43 is a front view thereof;
FIG. 44 is a rear view thereof;
FIG. 45 is a right side view thereof;
FIG. 46 is left side view thereof;
FIG. 47 is a top plan view thereof;
FIG. 48 is a bottom plan view thereof;
FIG. 49 is a front, top, left perspective view of a seventh embodiment of a box;
FIG. 50 is a rear, top, right perspective view thereof;
FIG. 51 is a front view thereof;
FIG. 52 is a rear view thereof;

FIG. 53 is a right side view thereof;
FIG. 54 is left side view thereof;
FIG. 55 is a top plan view thereof; and,
FIG. 56 is a bottom plan view thereof.
